HOLDER FOR CIGARETTES AND MATCHES

Annar F. Syverud, Minneapolis, Minn.

Application August 14, 1948, Serial No. 44,325

2 Claims.

(Cl. 206—1)

1

This invention has relation to a holder for cigarettes and matches of character adapted to be mounted upon a support, such, for example, as the dash of an automotive vehicle.

An object of the invention is to provide a holder for cigarettes and matches which will be of simple, inexpensive, practical, new and improved construction.

A further object is to provide a holder for cigarettes and matches wherein will be incorporated desirable and improved features and characteristics novel both as individual entities of the holder and in combination with each other.

And a further object is to provide a holder for cigarettes and matches of construction and operative in the manner as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawing forming a part of this specification,

Fig. 1 is a front elevational view of a holder for cigarettes and matches made according to the invention;

Fig. 2 is a longitudinal sectional view, taken on line 2—2 in Fig. 1;

Fig. 3 is a transverse sectional view, taken on line 3—3 in Fig. 1; and

Fig. 4 is a perspective view, on a reduced scale, disclosing the holder in open position.

Speaking generally, the holder which the invention presents is constituted as a pair of box-like members, denoted 10 and 11, respectively. The box-like member 10 is adapted to be mounted upon a support, as, for instance, the dash of an automotive vehicle, and the box-like member 11 is pivotally connected to said box-like member 10.

The box-like member 10 is of rectilinear configuration. It consists of a base wall 12, comprising a rear wall of the holder, an end wall 13, at the upper end of said box-like member 10, comprising a top wall of the holder, and spaced apart, parallel side walls 14, 14. Said spaced apart, parallel side walls 14, 14 are perpendicular to and connected with the end wall 13, the side walls 14, 14 and said end wall 13 meet at upper corners of the box-like member 10, all of the end and side walls 13, 14, 14 are perpendicular to the base wall 12, and the lower end of said box-like member 10 is open.

2

The box-like member 11 also is of rectilinear configuration. It consists of a base wall 15, comprising a front wall of the holder, an end wall 16, at a lower portion of said box-like member 11, comprising a bottom wall of the holder, spaced apart, parallel side walls 17, 17, and parallel extension portions 18, 18 upon said side walls 17, 17 and extending below the end wall 16. The spaced apart, parallel side walls 17, 17 are perpendicular to and connected with the end wall 16, said side walls 17, 17 and said end wall 16 meet at lower corners of the box-like member 11, all of the end and side walls 16, 17, 17 are perpendicular to the base wall 15, and the upper end of said box-like member 11 is open.

The side walls 17, 17 and the extension portions 18, 18 are situated between and in contiguous relation to the side walls 14, 14, and the extension portions 18, 18 are pivotally supported upon lower parts of the side walls 14, 14, by a transversely extending shaft 19 having its opposite end portions situated in said extension portions 18, 18 and said side walls 14, 14, for swinging movement of the box-like member 11 relative to the box-like member 10 between a closed position, as in Figs. 1, 2 and 3, and an open position, as in Fig. 4.

The rearward edges 20, 20 of the extension portions 18, 18 are in oblique relation to the end wall 16 to extend downwardly and forwardly therefrom, away from the base wall 12 when the box-like member 11 is in closed position, both to permit swinging movement of said box-like member 11 away from the box-like member 10 and to provide stops for limiting the extent to which the box-like members can be swung apart. That is, lower portions of the rearward edges 20, 20 below the transversely extending shaft 19, engage the forward surface of the base wall 12 to limit the extent of opening movement of the box-like member 11. Said box-like member 11 is disclosed in wide open position in Fig. 4, and engagement of lower portions of the rearward edges 20, 20 with the forward surface of the base wall 12 precludes swinging movement of the box-like members apart to an extent greater than disclosed in said Fig. 4. When the box-like member 11 is in closed condition, the rearward edges of its end and side walls 16, 17, 17 desirably will be contiguous with or closely adjacent to the forward surface of the base wall 12, about as disclosed in Figs. 2 and 3.

A curled spring 21, upon the transversely extending shaft 19 and having its opposite ends secured to the end wall 16 and the base wall 12, respectively, is for normally urging the box-like member 11 to its wide open position, as in Fig. 4.

The construction and arrangement are such that the upper edge 22 of the base wall 15 will lie beneath and contiguous with or closely adjacent to the lower surface of the forward portion of

the end wall 13 of the box-like member 10 when the box-like member 11 is in closed condition, as in Fig. 2, and the upper edges of the side walls 17, 17 of said box-like member 11 are cut away, as at 23, 23, to be clear of said end wall 13 thus to permit free swinging movement of the box-like members relative to each other.

A latch for retaining the box-like member 11 in its closed position, against action of the curled spring 21 tending to open said mentioned box-like member, is constituted as a leaf spring 24 beneath the end wall 13 and having its rearward end riveted, as at 25, to said end wall 13. The leaf spring 24 extends forwardly and slightly downwardly from the location where it is secured to the end wall 13, and the forward end portion of said leaf spring is shaped to provide an upwardly facing hook 26. The construction and arrangement are such that the forward end portion of the leaf spring will extend through an opening 27 in an upper portion of the base wall 15 when the box-like member 11 is in closed condition and the hook 26 will be engaged against a forward surface of said base wall 15 above and adjacent to the opening 27 thus to retain said box-like member 11 in closed condition. The hook 26 can be manually depressed to allow the curled spring 21 to swing the box-like member 11 to open position. Upon movement of said box-like member to closed position, said hook 26 will be urged by the leaf spring 24 into engagement with the forward surface of the base wall 15, in the fastened-closed condition of said box-like member 11. The fastening and unfastening operation will be apparent from Fig. 2.

The holder will be of size to contain a package of cigarettes when in closed position, and when the holder is in open position the cigarettes will be accessible.

Openings 28 in the base wall 12 of the box-like member 10 are for receiving means for mounting the holder upon a support, as upon the dash of an automotive vehicle.

A supporting means for a packet of matches, supported upon the base wall 15 of the box-like member 11 at the front thereof, is constituted as a bar 29 and a keeper 30 for said bar. One end portion of said bar 29 is situated in an opening 31 through a part of said base wall 15 at a side thereof and is bent or shaped, as at 32, to provide a pivotal support for the bar, and the other end portion of said bar is situated beneath the keeper 30. More explicitly stated, the pivotally supported end portion of the bar 29 is bent to S-shape and supported upon the base wall 15 in such manner that said bar can be swung from and toward said base wall 15 and upwardly and downwardly, and the keeper 30 is adapted to retain the bar 29 in slightly spaced, parallel relation to the base wall 15. Said keeper as disclosed is constituted as a generally L-shape clip having a shorter arm thereof secured, as at 33, to the base wall 15 and extending forwardly therefrom and a longer arm thereof extending downwardly in spaced, parallel relation to said base wall 15.

The supporting means above described is adapted to retain a packet of matches in such manner that the folder of said packet is situated and clamped between the bar 29 and the base wall 15 and the striking part of the packet faces forwardly. The bar 29 is releasable from the keeper 30 in order that packets of matches can be inserted in the holder and empty packets can be removed. The construction and arrangement desirably will be such that the folder of a packet

retained on the holder will be grasped between the bar 29 and the front surface of the base wall 15 of the box-like member 11.

What is claimed is:

5. In a holder, a support for a packet of matches constituted as a wall having a slot, a generally L-shape keeper mounted on an outer surface of said wall at a location spaced from said slot, and a packet supporting member including a flat, elongated bar adjacent said outer surface of said wall, a flat S-shape end portion contiguous with said flat bar and extending through said slot and a pair of ears contiguous with and projecting outwardly from opposite sides of said S-shape end portion at an end of said packet supporting member in direction transversely of said elongated bar, situated adjacent an inner side of said wall and of dimension to preclude passage of said end of the packet supporting member through said slot in the wall, whereby to provide for limited pivotal movement of said packet supporting member in a plane parallel to said wall thus to permit said bar to be moved into and out of engaged relation with said keeper.

20 2. A holder for a package of cigarettes and a packet of matches, comprising a package retainer constituted as a first box-like member adapted to be mounted on a support, a second box-like member having a front wall with a slot therein and a bottom supporting wall, one of said box-like members providing oppositely disposed side supporting walls, and means pivotally connecting lower portions of the first and second box-like members for swinging movement of the second box-like member between closed and open positions, and a packet supporter constituted as said front wall, a generally L-shape keeper mounted on an outer surface of said front wall at a location spaced from said slot, and a supporting member including a flat, elongated bar adjacent the outer surface of said front wall, a flat, S-shape end portion contiguous with said flat bar and extending through said slot in said front wall and a pair of ears contiguous with and projecting outwardly from opposite sides of said S-shape end portion at an end of said supporting member in direction transversely of said elongated bar, situated adjacent an inner side of said front wall and of dimension to preclude passage of said end of the supporting member through said slot in the front wall, whereby to provide for limited pivotal movement of said supporting member in a plane parallel to said front wall thus to permit said bar to be moved into and out of engaged relation with said keeper.
